APPARATUS FOR COATING CUP-SHAPED ARTICLES

Edwin K. Williams, Indianapolis, Ind., and Ben L. Wright, Chicago, Ill., assignors to Western Electric Company, Incorporated, New York, N. Y., a corporation of New York

Application April 12, 1951, Serial No. 220,595

3 Claims. (Cl. 118—215)

1 This invention relates to apparatus for coating articles, and more particularly to apparatus for printing ink coatings on cup-shaped articles.

An object of the invention is to provide new and improved apparatus for coating articles.

A further object of the invention is to provide apparatus for printing ink coatings on cup-shaped articles.

Another object of the invention is to provide apparatus for coating the generally frustoconically shaped bottom portions of cup-shaped articles.

An apparatus illustrating certain features of the invention may include a printing member for entering a cup-shaped article and printing the entire bottom portion thereof. The printing member may include a frustoconical platen composed of highly compressible material and an inking roll composed of a highly compressible material for applying a coating liquid to the printing face of the printing member.

A complete understanding of the invention may be obtained from the following detailed description of an apparatus forming a specific embodiment thereof, when read in conjunction with the appended drawings, in which

Fig. 1 is a fragmentary, side elevational view of an apparatus forming one embodiment of the invention with portions thereof broken away to show some of the elements more clearly.

Fig. 2 is a fragmentary, vertical section taken along line 2—2 of Fig. 1;

Fig. 3 is a generally, horizontal section taken along line 3—3 of Fig. 1;

Fig. 4 is a fragmentary, stepped, horizontal section taken along line 4—4 of Fig. 1;

Fig. 5 is a generally, vertical section taken along line 5—5 of Fig. 1;

Fig. 6 is a vertical section taken along line 6—6 of Fig. 1;

Fig. 7 is a generally, vertical section taken along line 7—7 of Fig. 1;

Fig. 8 is a fragmentary, rear elevational view taken along line 8—8 of Fig. 1;

Fig. 9 is a fragmentary, horizontal section taken along line 9—9 of Fig. 4;

Fig. 10 is a fragmentary, vertical section taken along line 10—10 of Fig. 1, and

Fig. 11 is a fragmentary, side elevation of the apparatus shown in Fig. 1 with portions thereof broken away.

Referring now in detail to the drawings, there is shown therein an apparatus for applying a printing ink, such as, for example, linseed oil base printing ink to a face 20 of a dial number plate 21 composed of cellulose acetate butyrate,

after which the coating is dried to a hard condition. The face 20 is of a generally frustoconical shape. The dial number plate 21 is placed in a socket 22 formed in a holder 23 of a drawer 24, which is movable into and out of a housing 25 along a guideway 26 by a handle 27 (Fig. 1). The handle is secured to the drawer 24 by rods 30—30 having stops 31—31 formed on the ends thereof, and springs 32 press the handle 27 to the left, as viewed in Fig. 1. To load the apparatus, the operator places the number plate 21 in the holder 23, and pushes the drawer 24 into the housing 25 until a stop 35 fixed to the holder engages the housing, in which position the dial number plate 21 is properly located beneath a printing pad 36.

The operator pushes the handle 27 farther to the right, as viewed in Fig. 1, and the rods 30—30 engage arms 40—40 (Figs. 1 and 7) fastened rigidly to a shaft 41 and turn the shaft 41 in a counterclockwise direction, as viewed in Fig. 1. This turns an arm 42 fastened to the shaft 41 in a counterclockwise direction to pull downwardly a spring-pressed lever 45 through a link 46 to actuate a valve 47. Actuation of the valve 47 causes air under pressure to be supplied to the upper end of a cylinder 50, and connects the lower end thereof to exhaust, thereby driving a piston 51 downwardly, as viewed in Fig. 1. The piston moves downwardly a holder 52 (Fig. 2) supporting the printing pad 36, and moves the pad 36 downwardly into engagement with the face 20 of the number plate 21. The pad 36 has an annular groove 55 therein designed to fit over a rib 56 formed on the dial number plate 21, the operator may release the handle 27 to permit the spring-pressed arm 45 (Fig. 1) to return the valve 47 to normal, and air under pressure is supplied to the lower end of the cylinder 50 and is exhausted from the upper end thereof, whereby the piston 51, the holder 52 and the pad 36 are moved upwardly to the retracted positions thereof shown in Figs. 1 and 2.

Whenever the holder 52 is moved downwardly, an arm 60 fixed to a shaft 61 is pivoted in a counterclockwise direction, as viewed in Fig. 1, by gravity, and swings an arm 62 in a counterclockwise direction. The arm 62 swings a pin 65 carried thereby downwardly to the right into engagement with a notch 66 formed in a pivotally mounted pull rod 67, which is in a retracted position at this time. When the holder 52 is raised thereafter, it swings the arm 60 in a clockwise direction and the pin 65 pulls the pull rod 67 to the left to its operating position, as shown in full-lines in Fig. 1, against the action of a spring-pressed lever 70 of a four-way valve 71 controlling

the intake and exhaust of air from a cylinder 72. A link 75 connects the lever 70 to the pull rod 67, and the pull rod 67 is mounted slidably on a pin 76 which projects through a slot 77 formed in the pull rod.

Whenever the control rod 70 is thus actuated, it causes air under pressure to be supplied to the righthand end of the cylinder 72, as viewed in Fig. 1, and exhausted from the lefthand end of the cylinder. This moves a piston 80 to the left, which moves a roller 81 carried by a yoke 82 fastened adjustably to the piston 80 out of engagement with a driven roll 85 and across the entire face of the pad 36. The roll 81 is composed of highly compressible material, such as rubber, neoprene (polymerized chloroprene), or the like, and is mounted on a core 86 supported by guide rolls 87-87 rolling on cam tracks 88-88. The cam tracks force the roll 81 tightly against the pad 36 so that the roll 81 compresses somewhat and the pad 36 compresses somewhat, and the entire lower face of the pad 36 receives ink from the roll 81. Adjustable stop rods 89-89 hold the holder 52 against movement upwardly when the pad 36 and the roll 81 are in compressive engagement. The tracks 88-88 force one of the rolls 81-87 into engagement with a wedge portion 90 formed on the pull rod 67 as the pad 36 is completely inked, and lifts the pull rod 90 out of engagement with the pin 65. The spring-pressed arm 70 then pulls the pull rod 67 to the right to its retracted position in which the notch 66 is substantially to the right of the pin 65. This movement of the arm 70 causes air under pressure to be supplied to the lefthand end of the cylinder 72, as viewed in Fig. 1, and air to be exhausted from the righthand end thereof, and the piston 80 is moved to the right to move the roll 81 back to the right out from under the pad 36 and into engagement with the roll 85.

Whenever the pull rod 67 is pulled from its retracted position, a pin 95 secured longitudinally thereto swings a lever 96 in a clockwise direction on a mounting pin 97. During the initial portion of the movement of the lever 96, a roll 100 is swung out of engagement with a driven roll 101 and into engagement with an inking roll 102. The lever continues to be swung in a clockwise direction, and the roll 100 moves to the left with respect to the arm of the lever mounting it against the action of a spring 105 holding the roll 100 in a slot 106. On the continued movement of the lever 96, it pivots a pawl actuator 107 through a link 110 having an adjustable, lost motion connection with the actuator 107. As the actuator 107 is swung in a clockwise direction, as viewed in Fig. 1, a cam-shaped pawl 111 turns a ratchet wheel 112 rigidly secured to the roll 102 to turn the roll 102 through a predetermined angle, and a supply of ink in a container 115 coats the roll 102, which rolls the freshly applied ink onto the roll 100. An adjustable doctor blade 116 secured to the container 115 regulates the thickness of the ink applied to the roll 102. Then, whenever the pull rod 67 is moved to the right from its full-line position, a tension spring 120 secured to the lever 96 swings the lever 96 in a counterclockwise direction to move the roll 100 out of engagement with the roll 102, and into engagement with the driven roll 101, and the pawl 111 is slid back around the ratchet 112 without moving the ratchet.

The rolls 85 and 101 are driven in the same direction by a belt 124 (Fig. 4) and pulleys 122, 123

123 and 124, the pulley 122 being driven continuously by an electric motor 125. The roll 101 rotates the roll 100 and receives the ink from the surface of the roll 100 onto its own surface. The rolls 85 and 101 also rotate a floating roll 130 mounted on a core 131 slidable in arms 132-132 fastened together by a handle 133. The ends of the core 131 fit into U-shaped notches 136-136 formed in the walls of the housing 25. A pin 140 carried by a rod 141 rigidly fastened to the housing 25 fits into a cam slot 142 formed in a cylindrical cam 145 fixed rigidly to the core 131 to slide the core 131 and the roll 130 back and forth along the axis thereof as the roll 130 is rotated by the rolls 85 and 101.

Operation

With the drawer 24 pulled out, the operator places the dial number plate 21 in the socket 22 in the holder 23, pushes the handle 27 to the right, as viewed in Figs. 1 and 4, to push the drawer in the housing 25, and then continues to press the handle 27 to the right to pivot arms 40-40 in a counterclockwise direction. This actuates the valve 41 to cause the piston 51 to be moved downwardly, and the pad 36 carried by the holder 52 is pressed against the generally frustoconical surface 20 of the dial number plate 21 to deposit ink thereon. The operator then releases the handle 27, and the springs 32-32 move the rods 30-30 to the left out of engagement with the arms 40-40. The spring-pressed arm 45 swings in a counterclockwise direction to return the arms 40-40 to their normal positions, and actuates the valve 41 to a condition in which the piston 51 is raised.

As the holder 52 is raised, it swings the arm 62 in a clockwise direction, as viewed in Fig. 1, through the arm 60, and the pin 65 enters the notch 66 and pulls the pull rod to the left from its retracted position. This swings the arm 70 in a counterclockwise direction to actuate the valve 71 to supply air under pressure to the righthand end of the cylinder 72 and exhaust air from the lefthand end of this cylinder. This forces the roll 81 to the left, out of engagement with the roll 85, rotating the roll 81 and applying ink thereto, and the roll 81 is rolled across the pad 36 and is compressed sufficiently to apply ink to the entire lower face of the pad 36. The cam tracks 88-88 and the stop rods 89-89 hold these two elements in tight compressive engagement. Then one of the rollers 87-87 engages the wedge portion 90 of the pull rod 67 and forces the pull rod upwardly to raise it above the pin 65 and release it from the pin. The spring-pressed arm 70 then pulls the pull rod 67 back to the right to actuate the valve 71 to supply air under pressure to the lefthand end of the cylinder 72 and exhaust the righthand end thereof. This pulls the roll 81 back across the pad 36 and completely out from under thereof and into engagement with the roll 85.

As the pull rod 87 is moved to the left, as viewed in Fig. 1, the pin 95 turns the lever 96 in a clockwise direction to sequentially swing the roll 100 out of engagement with the driven roll 101 and into engagement with the inking roll 102, and then turns the inking roll 102 through a predetermined angle to apply a predetermined stripe of ink onto the roll 100. Then, when the pull rod 67 is moved back toward the right to its normal position, the spring 120 (Fig. 4) moves the roll 100 into pressing engagement with the roll 101 and the roll 100 is rotated thereby. As

the roll 100 is rotated by the roll 101, the ink from the surface of the roll 100 is applied to the roll 101. Then the roll 101 transfers this ink to the floating roll 130, which is continuously reciprocated longitudinally relative to the roll 101 to spread the ink uniformly onto the roll 85, upon which the roll 130 also rests and is driven by. The roll 85 applies the ink to the roll 81 preparatory to the coating operation. Meanwhile, as soon as the roll 81 is moved back to its position of rest, the operator pulls the drawer 24 out of the housing 25 and removes the dial number plate 21. The operation described hereinabove then may be repeated with another uncoated number plate (not shown).

The apparatus described hereinabove supplies uniform ink coatings to non-flat surfaces of cup-shaped articles with a minimum of attention by the operator and works very rapidly. The unloading and loading operation may be effected while the holder 52 and the pad 36 is being reinked, so that the apparatus may be used to coat articles at a high rate of speed.

It is to be understood that the above-described arrangements are simply illustrative of the application of the principles of the invention. Numerous other arrangements may be readily devised by those skilled in the art which will embody the principles of the invention and fall within the spirit and scope thereof.

What is claimed is:

1. A coating apparatus, which comprises a housing having a trackway therein, a cylinder mounted in the housing extending generally transversely of the trackway, a piston operable by the cylinder, a stamp pad carried by the piston and movable thereby toward and away from the trackway, a drawer slideable along the trackway into and out of the housing, a valve for controlling the operation of the piston and the cylinder, lost-motion means carried by the drawer for actuating the valve to cause the piston to move the pad into engagement with an article carried by the drawer and to move the pad out of engagement with the article, a series of inking rolls, a pressing roll, a second cylinder mounted pivotally, a second piston carrying the pressing roll and operable by the second cylinder, a second valve for controlling the second cylinder, a pull rod, means operable by the pad for actuating the pull rod as the pad is moved away from an article to actuate the valve to cause the second piston to move the pressing roll out of engagement with the inking rolls and across the pad in compressive engagement therewith, means carried by the pressing roll for actuating the pull rod to reverse the second valve and to retract the pressing roll from the pad back into engagement with the inking roll, a fountain roll, a transfer roll movable between a position engaging the fountain roll and a position engaging one of the inking rolls, pawl and ratchet means for rotating the inking rolls, a fountain containing a supply of ink in engagement with the fountain roll, means for sequentially moving the transfer roll out of engagement with the inking rolls and into engagement with the fountain roll and for turning the fountain roll through the pawl and ratchet means through a predetermined angle to apply a predetermined stripe of ink to the transfer roll, 70 and means for moving the transfer roll out of engagement with the fountain roll and into engagement with one of the inking rolls.

2. A coating apparatus, which comprises a housing having a trackway therein, a cylinder 75

mounted in the housing extending generally transversely of the trackway, a piston operable by the cylinder, a resilient, cup-shaped stamp pad carried by the piston and movable thereby toward and away from the trackway, a drawer slideable into and out of the housing along the trackway for supporting a cup-shaped article, a valve for controlling the operation of the piston and the cylinder, lost-motion means carried by the drawer for actuating the valve to cause the piston to move the pad into engagement with the cup-shaped article carried by the drawer and to move the pad out of engagement with the article, a series of inking rolls, a resilient pressing roll, a second cylinder mounted pivotally, a second piston carrying the pressing roll and operable by the second cylinder, a second valve for controlling the second cylinder, a pull rod, means operable by the pad for actuating the pull rod as the pad is moved away from an article to actuate the valve to cause the second piston to move the pressing roll out of engagement with the inking rolls and across the pad in compressive engagement therewith, means carried by the pressing roll for actuating the pull rod to reverse the second valve and to retract the pressing roll from the pad back into engagement with the inking roll, a fountain roll, a transfer roll movable between a position engaging the fountain roll and a position engaging one of the inking rolls, pawl and ratchet means for rotating the inking rolls, a fountain containing a supply of ink in engagement with the fountain roll, means for sequentially moving the transfer roll out of engagement with the inking rolls into engagement with the fountain roll and for turning the fountain roll by the pawl and ratchet means through a predetermined angle to apply a predetermined stripe of ink to the transfer roll, and means for moving the transfer roll out of engagement with the fountain roll into engagement with one of the inking rolls.

3. A coating apparatus, which comprises a housing, a cylinder mounted in the housing, a piston operable by the cylinder, a resilient stamp pad carried by the piston and reciprocable thereby, a holder slideable into and out of the housing for moving an article into and out of alignment with the cylinder, means operable by the holder for actuating the cylinder to cause the piston to move the pad into engagement with an article carried by the holder and to move the pad out of engagement with the article, a series of inking rolls, a resilient pressing roll, a second cylinder mounted pivotally, a second piston carrying the pressing roll and operable by the second cylinder, and means for actuating the second cylinder to reciprocate the pressing roll out of engagement with the inking rolls and across the pad in compressive engagement therewith and back into engagement with the series of inking rolls.
